UNITED STATES PATENT OFFICE.

GUSTAVUS TROXLER, JR., OF NEWARK, NEW JERSEY, ASSIGNOR OF ONE-FIFTH TO HIMSELF, ONE-FIFTH TO ALEXANDER OBER, ONE-FIFTH TO ROBERT NEIL, AND ONE-FIFTH TO THEODORE PERRY, OF NEWARK, NEW JERSEY, AND ONE-FIFTH TO ARTHUR H. MOORE, OF JERSEY CITY, NEW JERSEY.

TROLLEY-WHEEL.

No. 833,353.

Specification of Letters Patent.

Patented Oct. 16, 1906.

Application filed October 10, 1905. Serial No. 282,130.

To all whom it may concern:

Be it known that I, GUSTAVUS TROXLER, Jr., a citizen of the United States, residing at Newark, in the county of Essex and State of

5 New Jersey, have invented certain new and useful Improvements in Trolley-Wheels; and I do hereby declare the following to be a full, clear, and exact description of the invention, such as will enable others skilled in the art to 10 o which it appertains to make and use the same, reference being had to the accompanying drawings, and to numerals of reference marked thereon, which form a part of this specification.

15 My present invention has reference generally to improvements in trolley-wheels and guards for electric railways; and the invention relates more particularly to that class of 20 trolley-wheels and guards for electric railroads which derive their motive power from overhead feed-wires or conductors.

The principal purpose of this invention is 25 to provide a novel and simply-constructed trolley-wheel and guard therefor, the guard being operatively connected and rotating with the wheel proper, whereby the parts have been reduced to a minimum, and are less likely of becoming disarranged and inoperative.

30 A further object of this invention is to provide the wheel proper with a series of yielding fingers directly connected with the wheel and normally having portions which extend beyond the periphery of the wheel and move 35 on opposite sides of the wire, so as to act as guards to prevent accidental displacement of the trolley-wheel from the wire, said fingers yielding against contact with the cross or supporting wires or when brought in contact 40 with the crossovers or turnouts in the feed-wire without any damage to the various parts of the wheel and the cross-wires and devices placed in the main feed-wire.

45 A further object of the present invention is to provide a trolley-wheel and novel guard therefor which will not interfere with the forward or rearward rolling engagement of the trolley-wheel against the feed-wire, the guard or fingers of the wheel being yieldable in 50 either direction and the parts being readily

and quickly adjusted in their operative relation with the feed-wire or conductor.

The construction of the device is such that although the trolley-wheel is guarded upon the feed-wire or conductor still there is no danger of the mechanisms and device injuring the cross-wires or supports or becoming disarranged by contact with said cross-wires or supports, as will hereinafter more fully appear.

With the various objects of my present invention in view the same consists in the novel trolley-wheel and guard therefor to be hereinafter more fully set forth; and, furthermore, this invention consists in the various 65 arrangements and combinations of the devices and parts, as well as in the details of the construction of the same, all of which will be described in detail in the following specification and then finally embodied in the clauses 70 of the claim, which are appended to and which form an essential part of this specification.

The invention is clearly illustrated in the accompanying drawings, in which—

Figure 1 is a side elevation of a trolley-wheel and novel guard therefor embodying the principles of the present invention, and Fig. 2 is an edge view of the same. Fig. 3 is a transverse section of the wheel and guard detached from the harp or wheel-carrier, 75 said section being taken through the wheel, and a pair of oppositely-placed and yielding guards or fingers which are pivotally connected with the wheel, certain connecting-springs between the several fingers and the 80 sides of the trolley-wheel being shown in elevation. Fig. 4 is a side elevation of the said trolley-wheel and guards or yielding fingers, the parts being represented in their operative relation with a feed-wire or support and 85 one set of the yielding fingers of the wheel being shown in yielding engagement with a 90 cross-wire or support.

Similar characters of reference are employed in all of the said above-described 95 views to indicate corresponding parts.

Referring now to the several figures of the drawings, the reference character 1 indicates a complete trolley-wheel and guard therefor embodying the principles of this invention. 100

2 indicates a portion of the main feed-wire or conductor, 3 a cross or supporting wire, and 4 one of the supports or hangers on said wire 3 for suspending the feed-wire 2 in its elevated position. The said trolley-wheel and guard comprises a suitable harp or trolley-wheel carrier 5, suitably connected at its lower end to a trolley-pole 6. The said harp or trolley-wheel carrier 5 is provided in its upper part with the yoke-shaped portions 7 or other means provided with bearings 8 for the pin or spindle 9, upon which is rotatively arranged a trolley-wheel 10, provided in its periphery with a channel or groove 11, adapted to be placed against the feed-wire or conductor 2 in the usual and well-known manner. The said trolley-wheel 10 is provided near its marginal peripheral edges with any desired number of pins or screws 12, the end portions of which project laterally from the opposite sides or flat faces of the said trolley-wheel 10, substantially as shown in Fig. 3 of the drawings. Said projecting ends of the pins or screws 12 are also preferably shouldered, as at 13, and are provided with the screw-threaded end portions 14 for the reception of a washer 15 and nut 16, substantially as illustrated. Pivottally arranged upon each laterally-projecting portion of said pins or screws and held in place by a washer 15 and nut 16 is the lower perforated end portion 18 of a guard or finger 17, the upper part 19 of each guard or finger extending beyond the marginal peripheral edge of the trolley-wheel 10.

In the lower end portion 18 each guard or finger 17 has a perforation 20 or other suitable fastening means, to which is attached the one end portion of a coiled spring 21, the opposite end portion of each spring being attached to the body of the wheel 10 by means of a post or pin 22 or other suitable fastening device.

Thus it will be seen from an inspection of the several figures of the drawings that each side face of the said trolley-wheel 10 is provided with any desired number of guards or fingers 17, which in their normal initial positions are caused by the tension of their respective springs 21 to extend in radial lines from the marginal peripheral edges of the wheel 10, but any one pair of which as it is brought in contact with the cross-wire 3 or the fixtures, such as crossovers or turnouts, carried by the wires, will easily yield against the obstruction thus presented, as clearly indicated in Fig. 4 of the drawings, without interfering with the usefulness of the trolley-wheel and its guard. As soon as the cross-wire or other obstructing fixture is passed the tensions of the distended coils of the springs 21 will immediately return the two yielding guard arms or fingers 17 to their initial and normally radially extending positions at the sides 60 of the wheel.

From the foregoing description and from an inspection of the several figures of the drawings it will be seen that the present invention provides a very simple and effectively-operating means for guarding a trolley-wheel upon the feed-wire or conductor against accidental displacement, and the construction of the parts is such that no injury to the cross-wires or supports for the feed-wire or to the parts of the trolley-guard is possible. Furthermore, it will be clearly evident that owing to the fact that the guard arms or fingers are attached to the wheel proper and rotate with the same in the majority of instances the uppermost guards or fingers will not come in engagement with the cross-wires, their ends passing either directly in front or back of the cross-wire without coming in contact with the same and reducing such contacting of these parts to a minimum.

Having thus described my invention, what I claim is—

1. The combination, with a trolley-wheel carrier, of a wheel carried by said carrier, a series of posts extending laterally from the opposite sides of said wheel, a radially-extending guard arm or finger extending from each post and rotatable with the wheel, and means connected with each guard-arm to produce the normally radial relation of each guard-arm, substantially as and for the purposes set forth.

2. The combination, with a trolley-wheel carrier, of a wheel carried by said carrier, a series of posts extending laterally from the opposite sides of said wheel, a radially-extending guard arm or finger pivotally arranged upon each post and rotatable with the wheel, and means connected with each guard-arm to produce the normally radial relation of each guard-arm, substantially as and for the purposes set forth.

3. The combination, with a trolley-wheel carrier, of a wheel carried by said carrier, a series of posts extending laterally from the opposite sides of said wheel, and a guard arm or finger pivotally arranged upon each post and rotatable with the wheel, and a spring between the lower end portion of each guard arm or finger and the body of the wheel, substantially as and for the purposes set forth.

4. The herein-described trolley-wheel and guard, comprising a wheel having laterally-extending posts upon its opposite sides, a guard arm or finger pivotally arranged upon each post, and means for normally causing said guard arms or fingers to extend in radial lines from the marginal peripheral edge of said wheel, substantially as and for the purposes set forth.

5. The herein-described trolley-wheel and guard, comprising a wheel having laterally-extending posts upon its opposite sides, a guard arm or finger pivotally arranged upon each post, and means for normally causing

said guard arms or fingers to extend in radial lines from the marginal peripheral edge of said wheel, consisting of a coiled spring for each guard arm or finger, each spring having 5 one end connected with a guard arm or finger and its opposite end secured to the body of the wheel, substantially as and for the purposes set forth.

In testimony that I claim the invention set forth above I have hereunto set my hand to this 25th day of September, 1905.

GUSTAVUS TROXLER, JR.
